UNITED STATES PATENT OFFICE.

FRANK SOLEY, OF PHILADELPHIA, PENNSYLVANIA, ASSIGNOR TO THE MILLER LOCK COMPANY, OF PHILADELPHIA, PENNSYLVANIA, A CORPORATION OF PENNSYLVANIA.

LOCK.

Application filed September 30, 1921. Serial No. 504,296.

To all whom it may concern:

Be it known that I, FRANK SOLEY, a citizen of the United States, residing in Philadelphia, Pennsylvania, have invented certain Improvements in Locks, of which the following is a specification.

My invention relates to certain improvements in locks of the type known as "cupboard" or "draw" locks.

One object of the invention is to simplify the construction of locks of this type and to construct the wards so that they can be readily shifted to make the necessary key changes.

A further object of the invention is to make the wards in the form of disks, which can be placed on a pivot pin.

In the accompanying drawings:

Fig. 1 is a plan view of my improved lock with the top plate removed;

Fig. 2 is a sectional view on the line 2—2, Fig. 1;

Fig. 3 is a sectional view on the line 3—3, Fig. 1;

Fig. 4 is a perspective view of the bolt;

Fig. 5 is a perspective view of the tumbler;

Fig. 6 is a perspective view showing three of the disk wards;

Fig. 7 is a perspective view of the spring;

Fig. 8 is a perspective view of the key hub;

Fig. 9 is a view of a modification showing the invention used in connection with another type of ward; and

Fig. 10 is a view showing a combination of the two wards illustrated in Figs. 1 and 9.

Referring to the drawings, 1 is the casing of the lock, which is pressed up from sheet metal, in the present instance. Formed integral with this casing are the side plates 2 and 3. 4 is the cover plate, which is secured to the casing of the lock in any suitable manner. In the present instance, the cover plate is notched to receive lugs on the casing and is also perforated for the passage of screws. In the casing are two studs, or pins, 5 and 6, on which the bolt 7 is mounted. The pin 5 projects through a slot 8 in the bolt and the pin 6 projects through a slot 9, as clearly shown in Fig. 1. The pin 5 is the pivot pin for the tumbler 10, Fig. 5, which has a lateral projection 11 that extends into a notch 12 in the upper edge of

the bolt 7 formed by a lip 13 so that, when the tumbler is raised, the bolt can be shifted 55 by the key and the projection 11 of the tumbler will drop back of the lug 13 of the bolt, holding the bolt in the projected position.

A spring 14 mounted on a pin 15 bears 60 against the casing and also against the projection 11, holding the projection yieldingly in the notch 12 on one side of the lug 13, or in the notch 16 on the opposite side of the lug. The pin 6 limits the downward movement of the tumbler, and the key hub 17 is so located in respect to its tumbler and the bolt that a key inserted in the tumbler and turned will first raise the tumbler and move the bolt into the projected or the retracted 65 position. A stop lug 18 on the bolt 7 limits the projection of the bolt.

Mounted on the pin 5 is a series of wards 19, 20 and 21. These wards are in the form of disks and, in the present instance differ in 70 diameter. The ward 19 is larger than the ward 20 and the ward 21 is smaller than the ward 20. These wards are so arranged in respect to the key hub 17 that they will extend into the notches in the key, and when 75 the proper key is inserted in the lock it can be turned clear of the ward disks and will operate the bolt.

A key change can be made by shifting the position of the wards on the pin 5. While 80 three wards are shown, a single ward may be used, or more than three.

In Fig. 9 a modification is shown, in which the wards instead of being in the form of disks are in the form of notched 85 bars 19^a, 20^a and 21^a, which fit over the two pins 5 and 6.

In Fig. 10 is shown a combination of the disk wards illustrated in Fig. 1 and the bar wards illustrated in Fig. 9.

The cover plate 4 is pressed up, as shown in Fig. 2, to receive the flanged portion 20 of the key hub 17. The opposite end of the key hub is reduced so as to project through the opening 21 in the casing 1. This arrangement tends to hold the key hub in proper alignment.

By the above construction, it will be seen that I am enabled to make a lock in which all of the parts can be stamped and cut into 105 shape, and in which a number of key changes can be made.

I claim:

1. The combination in a lock, of a casing having two pins; a bolt arranged to slide on said pins; a tumbler pivoted on one pin and arranged to engage the bolt either in its projected or retracted position; a spring tending to press the tumbler in engagement with the bolt; a ward mounted on one of the pins; and a key hub mounted in the lock 10 in such a position that a key inserted in the hub will move the tumbler and shift the bolt.
2. The combination in a lock, of a casing; two pins projecting from the casing; a bolt 15 slidably mounted on the pins; a tumbler arranged to engage the bolt; a spring for yieldingly holding the tumbler in engagement with the bolt; a series of disk wards mounted on one of the pins; and a key hub mounted in the casing in such position in respect to the wards and the bolt that a key 20 located in the key hub and turned will engage the tumbler and the bolt.
3. The combination in a lock, of a casing; a bolt; a tumbler for holding the bolt in its projected or retracted position; a key opening in the lock casing; and a series of disks 25 forming wards and arranged to project in the path of the key.

FRANK SOLEY.
